A. Rickart,
Turning Regular Forms.
No 17,846. Patented July 21, 1857.

Fig. 1

Fig. 2

UNITED STATES PATENT OFFICE.

ALEXANDER RICKART, OF SCHOHARIE, NEW YORK.

METHOD OF TURNING CARRIAGE-HUBS.

Specification of Letters Patent No. 17,846, dated July 21, 1857.

To all whom it may concern:

Be it known that I, ALEXANDER RICKART, of Schoharie, in the county of Schoharie and State of New York, have invented a new and 5 **5** Improved Machine for Turning Hubs for Wheels; and I do hereby declare that the following is a full, clear, and exact description of the same, reference being had to the annexed drawings, making a part of this 10 specification, in which—

Figure 1 is a side view of my improvement. Fig. 2 is a plan or top view of ditto.

Similar letters of reference indicate corresponding parts in the two figures.

15 My invention consists in having the gearing, by which motion is communicated from the driving or power shaft to the mandrel on which the "stuff" to be turned is placed, fitted in a vibrating frame, the lower end of 20 which is placed and allowed to move freely on the driving or power shaft, and the upper end connected to a sliding frame on which the mandrel is placed, the above parts being arranged as will be hereinafter fully shown 25 and described, whereby the "stuff" and cutter head may both be rotated from one and the same driving or power shaft, and the "stuff" fed to the cutter head without at all interfering with the gearing by which said 30 "stuff" is rotated.

To enable those skilled in the art to fully understand and construct my invention I will proceed to describe it.

A represents a rectangular frame on the 35 upper end of which a shaft or arbor B is placed transversely. On this arbor a cutter head C is fitted, the cutters (a) of which are made to conform to the intended pattern or shape of the hub to be turned, the cutter 40 head being of polygonal form and the cutters attached to its several sides.

In the lower part of the frame A a driving or power shaft D is placed transversely, from which shaft motion is communicated to 45 the arbor B by a belt (b). On the upper part of the frame A a sliding frame or carriage E is placed, the outer end of which is pivoted to a lever F, which is attached to the frame A at (c). This carriage is allowed to 50 work freely back and forth on the frame A and on its inner end a mandrel G is placed, said mandrel working between center points (d) (d) attached to the carriage.

On the shaft D the lower end of a frame H is placed or fitted loosely. This frame is 55 constructed of two bent or knee'd side pieces (e) (e) connected by cross ties. The form or shape of one of the side pieces is shown clearly in Fig. 1. In the frame H two shafts (f) (f') are placed, both of which are shown 60 in Fig. 2. On one end of the shaft D a pinion (g) is placed, and this pinion gears into a toothed wheel (h) which is placed at one end of the shaft (f) in the frame D, and at the opposite end of shaft (f) a pinion (i) is placed, 65 said pinion gearing into a toothed wheel (j) on one end of the shaft (f'), said shaft also having a pinion (k) gearing into a corresponding pinion (l) on the mandrel. The ends of the shaft (f') are fitted in the lower 70 ends of arms (m) (m) the upper ends of which are placed on the mandrel G.

I, is the "stuff" which is placed on the mandrel G. The carriage E is secured at any desired point on the frame A by means 75 of a pawl (a') which is attached to the carriage E catching into a rack (b') on the frame A.

From the above description of parts it will be seen that by having the mandrel G connected by means of the gearing in the frame H, with the driving or power shaft D as described, motion may be given to both the cutter head C and "stuff" I, from the same shaft D; and at the same time the carriage E 80 may be moved by the operator toward the cutter head and the "stuff" consequently fed to the cutters without interfering with the gearing which rotates the "stuff."

By this improvement the machine is rendered quite simple and effective.

The rotatory cutter head has long been used for the same or equivalent purposes and is a well known device; but I am not aware that a cutter head, and mandrel on which 95 the "stuff" to be turned is placed have both been driven with variable or different speeds from the same power shaft and the carriage in which the mandrel is placed allowed to slide or move while the parts are in operation, so that the "stuff" may be fed to the cutters. I do not claim separately therefore the rotating cutter head, but

What I do claim as new and desire to secure by Letters Patent, is—

The frame H placed on the driving or

power shaft D, and connected with the mandrel G, by the arms (m) (m), the frame H being provided with the gearing as shown to connect the shaft D with the mandrel G,
5 which mandrel is placed on the sliding carriage E, when the above parts are used in connection with the rotating cutter head C,

the whole being arranged substantially as and for the purpose set forth.

ALEXANDER RICKART.
